SELF-WINDING TIMEPIECE

Antoine Gazda, Providence, R. I.

Application February 28, 1952, Serial No. 273,808

2 Claims. (Cl. 58—82)

1

This invention relates to self-winding time pieces in general, and more particularly to self-winding watches adapted for mounting in vehicles.

An object of the invention is to provide a self-winding clock or watch particularly adaptable for mounting in the steering wheel of an automobile in full view of the operator.

Another object of the invention is to provide a self-winding clock or watch which is reliable in operation when mounted upon a vehicle subject to at least minute movements.

A further object of the invention is to provide a self-winding watch or clock which will wind the main spring of the mechanism regardless of the direction of the movements to which the vehicle is subjected.

A further object of the invention is to provide a self-winding watch or clock having a rotatably mounted pendulum for actuation of the main spring of the clock mechanism, and which pendulum on one side of the axis of rotation thereof is provided with an oscillating mass, and on the opposite side of the rotation axis with a quadrant having a plurality of pawls for coacting with a plurality of ratchet wheels driving through intermediate gears for winding the main spring of the mechanism.

In previous self-winding time pieces of this type, two pawls have coacted with a common single ratchet wheel and a non-uniform winding by the pawls has resulted.

In the present construction, due to the arrangement of the two pawls in conjunction with the plurality of ratchet wheels, a self-winding mechanism is provided in which the mechanism is wound uniformly by both pawls even at extremely small oscillation amplitudes of the pendulum. According to the present invention this is obtained in that each of the two pawls disposed on the same radial axis with respect to the axis of rotation of the pendulum and fixed at different distances from the axis of rotation, coact with superposed ratchet wheels of different diameters; the pawl lying farthest from the rotation axis of the pendulum coacting with a ratchet wheel of greater diameter than the ratchet wheel coacting with the pawl closest to the axis of rotation.

A still further object of the present invention is to provide in self-winding watches or clocks, having a rotatably mounted pendulum, shock absorbing means of different constructions to limit rotational movement of the pendulum and to absorb shocks in the clock mechanism.

2

Further objects and features of the present invention will be readily apparent from the following detailed description of preferred embodiments of the invention, taken together with the accompanying drawings. It will be obvious that the present invention is readily adaptable for mounting on all types of vehicles, and that suitable casings or mountings to fit the individual need can be utilized.

In the drawings:

Fig. 1 is a plan view of the winding mechanism of a self-winding watch showing the oscillatable pendulum and cooperating gears and ratchet wheels for winding the main spring of the clock;

Fig. 2 is a plan view of the pendulum for winding the main spring with the cooperating pawls and superposed ratchet wheels;

Fig. 3 is a vertical sectional view taken on the line 3—3 of Fig. 2;

Fig. 4 is a plan view of a modified form of pendulum showing shock absorbing means for the pendulum, parts being omitted for clarity;

Fig. 5 is a partial sectional view of the device shown in Fig. 4 taken on the line 5—5;

Fig. 6 is a plan view of a portion of a modified pendulum showing a modified shock absorbing construction; and

Figs. 7, 8 and 9 are partial views of three additional shock absorbing constructions of modified form.

In the drawings, a case 10 for containing the mechanism is shown and which case can assume any desired form or configuration. In the specific embodiment disclosed, the case is circular. The clock mechanism for actuating the hands of the clock with the exception of the main spring and cooperating gears is not shown on the drawings since it is not necessary for an understanding of the invention. It is also apparent that the specific gearing arrangement shown can be suitably modified within the skill of the art.

A main spring for the clock is shown at 11, and this spring is wound through a train of gears 12. The train of gears 12 has its lead gear driven by

a spur gear, not shown, which is fixed to a ratchet wheel consisting of superimposed individual ratchet wheels 13 and 14 rotatably mounted on pivot 15. A pendulum 16 is rotatably or oscillatably mounted in the center of the case on pivot 17.

It is not essential that the pendulum be centrally mounted in a case of different configuration. The pendulum 16 has a mass or weight 18 fixed at the end of one arm 19 of the pendulum and the opposite arm 20 of the pendulum is formed, radially opposed from the arm 19 with respect to the

pivot axis 17 as a sector having spaced arcuate surfaces 21 and 22 thereon.

In proximity to the surface 21, a pawl 23 is pivotally mounted for coaction with ratchet wheel 14 and spring biased by spring 24 to contact with the ratchet wheel. In proximity to the face 22, a second pawl 25 is pivotally mounted for coaction with ratchet wheel 13 and being spring biased into contact therewith by spring 26. The pivot points of the two pawls 23 and 25 are on the same radial axis with respect to the axis of rotation of the pendulum.

As can be seen from Fig. 1, the ratchet wheels 13 and 14 are mounted within the open sector of the arm 28 of the pendulum and are fixed with relation to one another for rotation about the pivot 15. The pawl 25 which lies farthest away from the rotation axis 17 of the pendulum 16 coacts with the larger ratchet wheel 13 and the pawl 23 closest to the rotation axis of the pendulum coacts with the smaller ratchet wheel 14. Due to this arrangement, both of the ratchet wheels, assuming equal oscillation magnitudes of the pendulum 16, are rotated by the pawls 23 and 25 through the same angle. Due to this arrangement, a uniform winding is achieved upon oscillation of the pendulum, and due to the opposite disposition of the two pawls, both of the ratchet wheels will always be rotated in the same direction.

For the purpose of limiting the oscillation movement of the pendulum within its effective orbit, and to prevent shocks to the clock mechanism, there is provided a member 27 which covers only a partial segment of a circle. On the free ends of the member 27 there are arranged compression springs 28 and 29. These compression springs are for coaction with the ends 30 and 31 of the weight 18 of the pendulum in an obvious manner.

In the form shown in Figs. 1-3 the pendulum consists of a hollow tubular member 32 closed on one side and containing a heavy metal 33, such for example as mercury, lead, or the like, of a specific gravity considerably higher than that of the metal of which the tube bow 32 is made. In this embodiment, the tube bow 32 is curved to correspond with the shape of the case 16.

The main spring can be provided with any suitable means to prevent overwinding.

In Fig. 4 of the drawings, a modified type of pendulum is shown. In the case 34 there is mounted a plate 35 having a cut out portion 36. Extending downwardly from the plate and radially disposed is an arm 37 which is fixed and stationary. A pendulum 38 is again oscillatably mounted by means of pivot 39. The upper arm 40 of this pendulum is the same as that shown in Fig. 1. The lower arm 41 of the pendulum has a mass or weight 42 to provide the necessary oscillation to the pendulum. The mass 42 has a cut out portion on the rear side thereof as shown at 43 which fits over and on opposite sides of the arm 37. The cut out portion 43 has fixed thereto on both sides compression springs 44. The arm 37 and springs 44, in conjunction with the limiting end surfaces of the cut out portion 43, limit the oscillation movement of the pendulum and at the same time serve as buffers or shock absorbers. Obviously the springs 44 could be mounted on the arm 37 instead of in the cut out portion and the same result would be obtained, as will appear hereinafter. The operation of this modified pendulum is the same as that described in connection with Fig. 1.

Fig. 6 shows a further modification of a pendulum which can be utilized in the present invention. Here the weight or mass at the lower end of the pendulum arm designated 45 has an opening or slot 46 therein preferably of oval arcuate shape. A post 47 of resilient material or covered by resilient material is fixed to the case and extends into the opening 46. On oscillation of the pendulum, the post 47 will coact with the extremities of the slot 46 for limiting movement of the pendulum, and serve as a buffer.

In Fig. 7 there is shown a modification of the arm 37 of Fig. 4 wherein instead of compression springs 44, curved springs 48 are secured on both sides of the arm for coacting with the cut out portion 43.

In Fig. 8 the arm 37 is shown as having spiral compression springs mounted on two opposed sides thereof for coaction with the cut out portion 43.

In Fig. 9 a post 47 is shown as having a resilient covering 49 thereon of any desired material for use in the modification shown in Fig. 6 of the drawings.

The operation of the device is believed to be obvious from the foregoing description. Whenever the vehicle is subjected to a movement, regardless of how slight, or if for example the steering wheel having a clock as above described mounted thereon is turned in any direction, the pendulum will oscillate in one direction or the other. Upon oscillation in either direction, the ratchet wheels 13 and 14 will be actuated always in the same direction by the pawls 24 and 25. The gear train 12 will accordingly be driven in a direction to wind the main spring of the clock and over-winding will, as set forth above, be prevented.

In previously known devices a large amplitude of movement or vibration was required in order to properly actuate the winding mechanism and the oscillation of the pendulum had to be continued over a considerable period of time in order to insure proper and adequate winding of the main spring of the clock. In the present device, however, due to the arrangement of the plurality of ratchet wheels and the specific arrangement and size thereof, in conjunction with the arrangement and placing of the pawls, insures a uniform winding with even the slightest movement. It has been found, for example, that with the present construction and arrangement mounted on the steering wheel of an automobile that sufficient winding of the main spring is obtained in approximately 25 miles of driving to maintain the clock in working condition for a period of 8 days. In previous known constructions, utilizing but a single ratchet wheel and not having the particular arrangement of the present invention, at least 40 miles were required for the same amount of winding, and such factors as the amount of movement or vibration of the vehicle seriously affected this winding.

It is obvious that various changes may be made in the form construction and arrangement of the parts without departing from the spirit and scope of the invention as defined in the appended claims.

I claim:

1. A self-winding time piece comprising a main spring for the time mechanism, a pair of ratchet wheels having different radii, means connecting said wheels with said spring, a pendulum, a pivot upon which said pendulum oscillates, a pair of spring biased pawls on said pendulum

coacting with said ratchet wheels, one of said pawls farthest from said pivot coacting with the larger of said ratchet wheels and the other of said pawls closest to said pivot coacting with the smaller of said ratchet wheels so that upon equal oscillation magnitudes of said pendulum said ratchet wheels are rotated by said pawls through the same angle.

2. A self-winding time piece adapted for mounting in vehicles comprising a main spring for the time mechanism, a plurality of concentric superposed ratchet wheels, a gear train connecting said ratchet wheels with said main spring, a pendulum oscillatably mounted on a pivot axis, said pendulum having diametrically opposed arms on opposite sides of its pivot axis, a pendulum weight on one arm of said pendulum, means on the other arm of said pendulum for coacting with and actuating said ratchet wheels to wind said main spring in response to oscillations of said pendulum, said means for actuating said ratchet wheels comprising pawls rotatably secured on said other arm of said pendulum differently spaced from the pivot axis of said pendulum, said ratchet wheels being also spaced from the pivot axis of said pendulum, each of said pawls coacting with a different said ratchet

wheel for actuating said ratchet wheels in the same direction when said pendulum oscillates in either of its directions, said pawls differently spaced from the pivot axis of said pendulum being arranged on opposite sides of said ratchet wheels for coacting with separate ones of said ratchet wheels, said ratchet wheels being two in number and of different radii, that pawl farthest from the pivot axis of said pendulum coacting with the larger of said ratchet wheels and the pawl closest to the pivot axis of said pendulum coacting with the smaller of said ratchet wheels, whereby upon equal oscillation magnitudes of said pendulum said ratchet wheels are rotated by said pawls through the same angle.
